UNITED STATES PATENT OFFICE.

ERWIN KLEIN, OF PEEKSKILL, NEW YORK.

PROCESS OF VINEGAR-MAKING.

1,272,276.

Specification of Letters Patent. Patented July 9, 1918.

Application filed January 12, 1916. Serial No. 71,692.

To all whom it may concern:

Be it known that I, ERWIN KLEIN, a subject of the Emperor of Austro-Hungary, residing at Peekskill, in the county of West 5 chester and State of New York, have invented certain new and useful Improvements in Processes of Vinegar-Making, of which the following is a specification, reference being had to the accompanying 10 drawings.

This invention relates to improvements in processes of making vinegar, and particularly to improvements in the Schutzenbach process of making vinegar. As is well known 15 to all persons skilled in this art, the Schutzenbach process of vinegar-making is carried out by causing a fluid mixture capable of undergoing acetic fermentation (hereinafter called the mix or wash) to flow downwardly through a vat (hereinafter designated as the generator) filled with wood shavings or like material affording an extensive surface. There is thus exposed to the action 20 of the vinegar microbes, in the presence of the oxygen of the air, a large surface of the mix (or wash), whereby the alcohol of the latter is changed to acetic acid with the evolution of heat; and the heat thus developed by the change just referred to produces a 25 draft (or chimney effect), whereby fresh air is caused to enter the generator through air-holes formed in the bottom thereof and flow upwardly over the mix. Thus the mix is brought into contact with the counter- 30 current of fresh air, which is gradually deprived of much of its oxygen and is finally discharged through the top of the generator as "spent" air. The Schutzenbach process hereinbefore briefly described is imperfect 35 in two important directions or features, namely: (1) The draft or chimney effect is dependent upon the difference between the temperature of the external atmosphere and the temperature existing within the genera- 40 tor; and (2) the ascending current of air increases the tendency of the mix to volatilize. One object of this invention is to provide a process of making vinegar which 45 will be susceptible of being so carried out as to be independent of external conditions, such as the temperature of the atmosphere and other external conditions. Another object of this invention is to standardize the 50 conditions under which the vinegar is made

and thereby to diminish greatly the losses 55 due to evaporation and to increase the yield of vinegar and the general efficiency of the plant.

In the drawings illustrating the principle of this invention and the best mode now 60 known to me of applying that principle, Figure 1 is an elevation, partly in section and somewhat diagrammatic in character, of a vinegar-making plant arranged and designed to carry out my new process; Fig. 2 65 is an elevation, partly in section, of the generator; Fig. 3 is a plan of the same; Figs. 4, 5 and 6 are sections on the lines 4—4, 5—5 and 6—6, respectively, of Fig. 2; Fig. 7 is a plan of one of the siphons with the cap 70 removed; Fig. 8 is a section on the line 8—8 of Fig. 7; Figs. 9 and 10 are sections on the lines 9—9 and 10—10, respectively, of Fig. 8; Figs. 11 and 12 illustrate in perspective 75 two shapes of the wooden bars or rails forming the false bottoms of the compartments; Figs. 13, 14 and 15 illustrate different forms of recorders for recording the quantity of mix (or wash) used; and Figs. 16 and 17 illustrate different forms of thermo-regula- 80 tor.

The mix (or wash) is forced through the pipe *a* which discharges into the tank *b* from which the mix is drawn and forced by the pump *c* through the pipes *d*, *e*, *f*, *g*. 85 The pipe *d* extends or projects above the pipe *e*, with which it communicates, and is connected with the pipe *d'*, so that any excess, surplus or overflow of the mix may be conducted by the pipe *d'*, back to the tank *b*. 90 The pipe *g* has, in the form illustrated, three outlets *h* each of which is controlled by a valve *i*. The mix (or wash) is, whenever necessary, cooled to a certain predetermined temperature in the following manner: The 95 pipe *a* is surrounded by a water-jacket *j* through which flows water that is forced into the pipe *k* and led therefrom to the water-jacket *j* by the water-pipes *m*, *m'*. The water is led from the water-jacket *j* by the water-pipes *n*, *n'*; the pipe *n'* discharges 100 into the sewer (not shown). A refrigerating engine *o* forces a refrigerating fluid through the coil *p* that is mounted in the tank *b* and serves to chill the mix (or wash) to any desired predetermined temperature before the mix is forced by the rotary pump *o* to the generator *A*.

Air is led through the pipe q into a tank r which is filled with a suitable liquid, such as dilute acetic acid or dilute sulfuric acid, below the level of which acidified liquid the pipe q extends. The air is thus cleansed, sterilized and moistened. From the tank r , the air is drawn through a pipe s by an air-compressor (shown diagrammatically at t) which forces the air through the pipe u that passes through the water-jacket v and brine-cooler w . The water-jacket v is fed by water that is led through the pipes k , x ; and water flows from the water-jacket v through the pipe y to the vertical pipe n' and through the latter to the sewer. The brine-cooler w is fed by a salt solution that is forced through it by the refrigerating engine o ; the circulation of the brine occurs through the pipes w' , w'' . A damper u' permits the flow of air through the air-pipe u to be controlled.

Beneath each outlet h , there is arranged an intermediate tank 2 (Figs. 7 to 10) which is automatically emptied by a siphon 3. The mix flows from the annular space 2' through the holes 2" in the cap 2* and then upwardly through the annular passage 2*, which forms one of the shorter legs of the siphon. From the passage 2*, the mix flows into the vertical passages 3*. The latter passages form the longer leg of the siphon. The central passage 4 is filled by mix flowing through the horizontal passages 3* and forms the other shorter leg of the siphon. The mix flows from the central passage 4 into the vertical passages 3*. The mix, flowing from these passages 3*, drops upon the curved surfaces 5' of the pyramidal-shaped base 5, which supports the intermediate tank 2. These curved surfaces 5' serve to distribute the wash or mix over the perforated distributing top or cover 6. The mix flows through the holes 7 therein down into the upper compartment 8 which, like the compartments 8', 8'', below it, is filled with shavings 9, of wood or the like. The floor-beams 10 support the false bottoms which are made of the spaced wooden bars or strips 11 having the shape shown in Fig. 11; that is, these strips of wood are rounded near the bottom so that the lower face 11' is devoid of corners to which drops of liquid might adhere. An alternative wedge-shaped form of strip is shown at 12 in Fig. 512 and may be used instead of the form shown at 11.

The air-pipe u discharges into a vertical air-pipe u'' from which lead the horizontally-disposed air-pipes 13, 13', 13'' controlled by the valves u^x . The front and back walls A'' of the generator A are formed with openings 14, 14', 14'', opposite the air-pipes 13, 13', 13'', respectively, and into these openings 14, 14', 14'', project the ends 65 of the spaced wooden bars 11 that form the

false bottoms or floors of the compartments 8, 8', 8''. The inside walls of the air-conduits 13, 13', 13'' (that is, the walls thereof opposed to the openings 14, 14', 14'', respectively) are formed with apertures 13* the degree of opening of which is controlled by slides 15, 15', 15'', respectively, which regulate the flow of the air from the pipes 13, 13', 13'', through the openings 13* into the spaces 11* between the floor strips 11 and, therefore, into the several compartments of the generator through these spaces 11*. The position of each of the slides 15, 15', 15'', is separately controlled and, for this purpose, there is provided for each slide a shaft 16 upon which are mounted the gears 17, each of which engages a rack 18 that is fastened to the slide. By turning one of the shafts 16, there will be moved that slide that carries the racks 18 in mesh with the gears 17 fast upon the actuated shaft 16. The fresh air that flows into the air-conduits 13'' escapes therefrom through the apertures 13*, passes into the spaces 11* between the bars, rails or strips of wood 11 that form the false bottom of the lowermost compartment 8'' and then flows upwardly therethrough, coming in contact with the mix and oxidizing the same. Thus, absolutely fresh air is intermingled with the mix just before the latter flows into the space 13* at the bottom of the generator A, and, in this way, it is insured that the oxidation of the mix and its resulting conversion into vinegar shall be as perfect or complete as practicable. The air, in flowing through the lowermost compartment 8'', becomes "spent" and on leaving this lowermost compartment, the spent air meets the fresh air that flows into the air-conduit 13' and, through the apertures 13* therein, issues therefrom and passes upwardly through the intermediate compartment 8'. In its passage through this middle compartment 8', the mixture of fresh and spent air becomes more and more exhausted of its oxygen; and, upon issuing from the intermediate compartment 8', the air current meets the fresh air flowing from the air-conduit 13 through the apertures 13* therein. This mixture of spent and fresh air flows upwardly through the topmost compartment 8 and meets therein the inflowing mix. The temperature of the latter is low, in fact, so low as to condense the vapors that are carried by the air current; and, by the condensation of these vapors, the loss due to evaporation is greatly reduced. As the mix progresses downwardly, it becomes less and less cool and soon is raised to a temperature at which an oxidizing reaction takes place. From the compartment 8, the air flows through the holes 7 in the perforated distributing top or cover 6 and thence flows upwardly through the chimney 18 past the damper 19 therein.

In order to create a draft in the flue or chimney 18, a fan 20 of acid-resisting material is rotatably mounted therein and is driven by a cone-pulley 22 belt-connected 5 with another cone-pulley 23 mounted upon a shaft 24 that is driven by a propeller 25 actuated by the flow of the mix through the pipe f . The action of the fan 20 is furthermore to reduce the pressure existing within 10 the generator A upon the vinegar microbes and thereby to facilitate the multiplication of the latter. The roof A' of the generator A is kept cool by an annular sprinkler 26 fed by water led through a pipe 27 that 15 is connected with the pipe m . The water flows from the sprinkler over the roof A' of the generator A and into the gutters 28 that discharge into the leader 29. In order to 20 keep the generator compartments 8, 8', 8'', A^x as free from atmospheric temperature influences as possible, the outside of the walls 25 of these compartments consists of a heat-insulating covering A''. The inner side of the walls A^x are furthermore lined 30 with an acid-proof material, which may be made of a fibrous substance combined with tar, asphalt and paraffin products; but it is to be understood that any suitable acid-resisting lining may be used in carrying out this invention. Between the acid-proof lining 30 and the heat-insulating covering A'', there are interposed boards 21.

In order to record the amount of mix that passes in a given time interval through 35 the siphon 3 shown in section in Fig. 8, a recording mechanism may be used; and three different forms of recording mechanisms for this purpose are illustrated in the drawings (Figs 13 to 15). In Fig. 13, 40 one arm 31' of a spring-controlled bell-crank lever 31 projects into the path of flow of the mix while the other arm 31'' of this lever 31' carries a marker 32. When no flow is taking place, the marker 32 is held 45 against the recording disk 33 by a spring 34; but, when a flow of the mix is taking place, the marker 32 will be withdrawn from the face of this disk 33, which is driven by clockwork 33'. In Fig. 14, an electric 50 circuit is completed between the insulated electric contacts 35, 35', by the mix when the same reaches the level of the electric contact 35 mounted in but insulated from the wall of the intermediate tank 2; and 55 the current flowing through this circuit energizes the magnets 36, which thereupon attract the armature 31' forming one arm of the bell-crank lever 31; and, when this armature 31' is attracted, the marker 32 60 is withdrawn as before, from the face of the recording disk 33. In Fig. 15, there is shown a float 37 buoyed up by the mix in the intermediate tank 2 and connected by a cord 38 with a rotatably mounted disk 39 65 to which is connected a weight 43. The

cord 38 passes over a pair of pulleys 41, 42, and the disk 39 carries a pivotally mounted pawl 40 one end of which is controlled by a spring 40'' and the other end or toe of which is arranged to engage the teeth 44' 70 of a ratchet-wheel 44 on the same shaft with which is mounted a pinion 45 that drives the toothed wheels of the counter 46. A stop 40' limits the upward throw of the longer arm of the pawl 40 under the action 75 of the spring 40''. As the level of the mix rises in the intermediate tank 2, the disk 39 is turned clockwise by the pull of the weight 43 hung from the disk 39 by the cord 43' and the toe of the pawl 40 engages 80 the ratchet teeth 44' and turns the ratchet wheel 44 and the pinion 45. When the mix is discharged from the intermediate tank 2 by the siphon 3, the float 37 falls and turns the disk 39 counter-clockwise and 85 winds up thereon the cord 43' carrying the weight 43. During this backward movement of the disk 39, the toe of the pawl 40 rides over the ratchet 43 without engaging the teeth 43' of the same; and a 90 guard-pawl 47 prevents any movement of the ratchet 43 during the retrograde movement of the disk 39. A spring 48 holds the pawl 47 against the stop 47.

In order to control with great nicety the 95 temperature of the mix in the storage tank b, there may be provided a thermo-regulator 49, the temperature-controlled element 52 of which projects into the tank b and the flow-controlling element 56 of which controls the 100 passage of the refrigerating fluid through the coil p from the refrigerating engine o. In a manner entirely similar, the flow of the brine through the pipe w' may be controlled by the thermo-regulator 50 and the temperature of the air flowing through the pipe u may be regulated with great accuracy. In Figs. 16 and 17, there are illustrated two forms of thermo-regulator capable of use in carrying out this invention. In the form 110 shown in Fig. 16, the bulb 52 contains mercury 53 on top of which rests a liquid 54 of low boiling point; that is, the boiling point of this liquid 54 is practically the maximum temperature permissible in the tank b, so 115 that, when that temperature is reached therein, the liquid 54 will boil and its vapor will increase the pressure in the bulb 52 to such a degree that the mercury will be forced out of the bulb 52 and through the conduit 55. In the pipe o', leading from the refrigerating machine o to the coil p, there is mounted 120 a slide-valve 56 formed with an opening 57 and having an upwardly-projecting arm 58 and a downwardly-extending leg or post 59 around which there is coiled a spring 60 that normally forces the slide-valve 56 upwardly so that its opening 57 is thrown out of register with the inlet end o'' of the pipe o' from the refrigerating machine; but, 130

when the liquid 54 boils and the mercury 53 is thereby forced through the conduit 55 and against the upper end of the arm 58, the pressure of the mercury 53 forces the slide-valve 56 downwardly, until the opening 57 formed therein registers with the inlet end o' of the pipe o' , whereupon the refrigerating fluid is free to flow therethrough from the refrigerating machine o . When this form of thermo-regulator is used to control the temperature of the air flowing through the air-conduit u , the bulb 52 is mounted in the latter and the slide-valve 56 controls the flow of the refrigerating fluid through the pipe w' .

In the form of thermo-regulator shown in Fig. 17, the thermometer 61 is mounted in the tank b and the mercury 53 serves to complete the electrical circuit between the contact-plates 62, 63, when the temperature in the tank b has risen to the permissible maximum. The electrical circuit having been completed, current will flow therethrough from the dynamo 64 and will drive the motor 65 which will, in turn, propel the centrifugal pump 66. This pump 66 will then draw the refrigerating fluid from the machine o through the pipe o' and will force that fluid through the coil p . Or the dynamo 64 may be used to drive the refrigerating machine o itself.

It is to be observed that the air supplied to the generator A is fresh air from the outside and not air that has been already viti-
ated or "spent" by having been one or more times brought into contact with the mix, as is the case where the generator is housed in a building and the air is, after passing through the generator, discharged within the building only to be fed to the generator again without having its oxygen fully replenished by mixing with the outer atmosphere. The air is carefully treated and thereby prepared for the reaction that takes place in the generator; thus, it is cleansed, sterilized and moistened by being sucked through acidulated water in the tank r or filtered through cotton or the like and is brought to exactly the proper temperature by coolers v , w ; a thermo-regulator 50 may with advantage be used in effecting this purpose. Moreover, if the temperature of the outside air be already too low, heaters may be substituted for the coolers v , w , of course. The mix is likewise brought to the proper temperature by means of the cooler j and coil p . The generator is divided by horizontally-disposed false-bottoms into sections or compartments 8 , $8'$, $8''$, one above the other in a vertical series through which the mix is allowed to flow from the top to the bottom of the generator. The topmost compartment 8 is used principally for the condensation of the vapors carried by the air-current that flows upwardly and passes out

through a flue 18, in which an upward draft is maintained by a fan 20 driven by the inflowing mix. It is furthermore to be noted that, while fresh air is led to each compartment separately and in quantities controlled by slides 15, 15', 15'', that are moved independently of one another, all the air introduced into the generator eventually flows through the topmost section where condensation of the vapors carried by the air is effected. The mix which flows into the lowermost compartment and has already been at least in part oxidized meets there and is acted upon by the absolutely fresh air supplied to that compartment, whereby the mix is fully oxidized and transformed into vinegar, when it is drawn off through the outlet spigot 51. Not only is separate control effected, as has been hereinbefore explained, of the quantity of the fresh air admitted to the several compartments but control is also effected by the valves i of the volume of mix admitted to the generator and a record of the quantity of mix so supplied is automatically made, to the end that accurate control thereof may be had. Again, instead of supplying the mix by one siphon of large capacity, several siphons 3 of small capacity are used and this arrangement results in the more even distribution of the mix over the surface of the perforated distributing top or cover 6; and the distribution of the mix thereover is made still more even by the use of surfaces 5' of the pyramidal-shaped bases 5 that support the siphons 3. The downward flow of the mix through the generator is facilitated by rounding off the lower edges of the strips 11 that make up the false-bottoms that separate the compartments and of the floor-beams 10 that support these false-bottoms. To make the reactions that take place within the generator still more independent of temperature conditions external thereto, and to make more complete the condensation of the vapors carried upwardly by the current of practically spent air, the roof A' of the generator A is kept wetted by water flowing over the roof, while the generator is in operation; and the walls A'' of the latter are covered with a heat-insulating material A''' . It may be further pointed out that, by using several siphons 3 of small capacity, there is eliminated the danger of improper starting, which danger is present when the siphon is one of large diameter.

As will be evident to all skilled in this art, changes may be made without departing from the spirit of this invention; thus, the air may be passed through a filter of cotton, in addition to the tank r of acidulated water; and a nozzle discharging steam into the flue 18 may be used instead of or in addition to the mix-controlled fan 20 for creating a draft. Other changes will

readily suggest themselves and all such changes are deemed by me to be covered by the claims which follow hereinafter.

I claim:

- 5 1. A step in the Schutzenbach process of vinegar-making, comprising automatically controlling the draft of spent air by the inflowing fluid mixture capable of undergoing acetic fermentation.
- 10 2. A step in the Schutzenbach process of vinegar-making, comprising condensing in a generator by means of the artificially precooled inflowing fluid mixture capable of undergoing acetic fermentation the vapors carried by the spent air.
- 15 3. A subprocess in the herein described Schutzenbach process of vinegar-making, consisting in condensing in a generator by means of the artificially precooled inflowing fluid mixture capable of undergoing acetic fermentation the vapors carried by the spent air; and finally subjecting the mixture to the action of fresh air.
- 20 4. A subprocess in the Schutzenbach process of vinegar-making, comprising precooking the fluid mixture capable of undergoing acetic fermentation; and condensing the vapors carried by the spent air, by introducing the precooled mixture near the top of the generator.
- 25 5. A subprocess in the Schutzenbach process of vinegar-making, comprising precooking the fresh air; controlling the internal temperature of the generator by passing the precooled fresh air therethrough in an ascending current; precooking the fluid mixture capable of undergoing acetic fermentation; and condensing the vapors carried by the spent air, by introducing the precooled mixture near the top of the generator.
- 30 6. A subprocess in the Schutzenbach process of vinegar-making, comprising precooking the fresh air; controlling the internal temperature of the generator by passing the precooled fresh air therethrough in an ascending current; precooking the fluid mixture capable of undergoing acetic fermentation; condensing the vapors carried by the spent air, by introducing the precooled mix-

ture near the top of the generator; and exhausting the spent air from the generator.

7. A subprocess in the Schutzenbach process of vinegar-making, comprising precooking the fresh air; controlling the internal temperature of the generator by passing the precooled fresh air therethrough in an ascending current; precooking the fluid mixture capable of undergoing acetic fermentation; condensing the vapors carried by the spent air, by introducing the precooled mixture near the top of the generator; and controlling the outflow of the spent air by the inflowing mixture.

8. A subprocess in the Schutzenbach process of vinegar-making, comprising artificially-cooling the generator by flowing portions thereof with cold fluid; introducing near the top of the generator the fluid mixture capable of undergoing acetic fermentation; and condensing the vapors carried by the spent air by bringing the same into contact with the cooled mixture and the artificially-cooled portions of the generator.

9. A subprocess in the Schutzenbach process of vinegar-making, comprising precooking the fresh air; regulating the temperature to which the latter is precooled; and controlling the internal temperature of the generator by passing the precooled fresh air therethrough in an ascending current.

10. A subprocess in the Schutzenbach process of vinegar-making, comprising precooking the fluid mixture capable of undergoing acetic fermentation; regulating the temperature to which the latter is precooled; and condensing the vapors carried by the spent air, by introducing the precooled mixture near the top of the generator.

Signed at Peekskill, N. Y., this seventh day of January, 1916, in the presence of the two undersigned witnesses.

ERWIN KLEIN.
